DEVICE FOR CARBONATING LIQUIDS IN
BOTTLES

George Francis Sugden, Marple Bridge, England,
assignor to SodaX (1929) Limited, London,
England, a British Company

Application December 16, 1933, Serial No. 702,829
In Great Britain December 19, 1932

8 Claims. (Cl. 226—67)

This invention relates to a new or improved apparatus for carbonating liquids in bottles.

The main object of the invention is to provide an apparatus which will enable a number of bottles in succession to be supported in the upright position and to be brought into gas-tight engagement with the gas delivery device while enabling the gas delivery tube from the gas delivery device to extend downwardly within the bottle.

10 A further object of the invention is to provide an apparatus which will enable a number of Crown cork bottles in succession to be held supported by their necks in the upright position and to be brought into gas-tight engagement with 15 the gas delivery device while enabling the gas delivery tube from the gas delivery device to extend downwardly within the bottle.

According to one feature of the invention this is accomplished by mounting the gas delivery 20 device so that it can be pivoted or otherwise moved in a direction outwardly from the bottle holding device. Upon displacement of the gas delivery device outwardly the gas delivery tube can be inserted in the bottle, the bottle placed in position on or in the bottle holder and the bottle and gas delivery device approximated towards each other to provide gas-tight engagement.

According to a further feature of the invention the bottle holding device is adapted to be displaced outwardly with respect to the gas delivery 30 device. Thus it is possible to place the bottle in position beneath the gas delivery device with the gas delivery tube extending downwardly therein and then to displace the bottle-holding 35 device beneath or around a part of the bottle so as to support it and finally to approximate the bottle and gas delivery device towards each other so as to provide a gas-tight joint.

Another important feature of the invention 40 consists in making the gas delivery device displaceable towards the bottle so that a gas-tight seal is obtained by displacement of the gas delivery device while the bottle is maintained stationary in or on the holding device.

45 In the modification of the invention in which the gas delivery device is made outwardly displaceable for the purpose of enabling the gas delivery tube to be inserted in the bottle, the bottle may be held either at its base or by its neck.

50 The holding of the bottle by its neck, however, is a further important feature of the invention and is believed to be broadly novel in apparatus of this kind. The employment of means for holding the bottle by the neck in conjunction with 55 a gas-delivery device which can be swung out-

wardly of the bottle neck holding device enables the apparatus to be used for bottles of different heights which have a standard size of neck, for example Crown cork bottles, without any alteration in the construction or arrangement of the machine.

The gas delivery device may in any of the modifications of the invention, comprise a gas chamber having a valve for admission of carbon dioxide under pressure and a valve for release 10 to the atmosphere for the purpose of shifting the contents of the gas chamber, if desired. Thus a two-way valve may be employed which in one position is closed, in a second position allows carbon dioxide to be fed to the gas chamber and 15 delivery pipe, and in a third position allows the gas chamber to be in communication with the atmosphere. Such a type of valve in conjunction with a gas chamber is known of itself for the purpose of carbonating liquids.

20 One preferred form of the invention is illustrated in the accompanying drawings in which

Figure 1 is a side elevation of a hand apparatus,

Figure 2 is a side elevation of the same apparatus showing a bottle of the Crown cork type being inserted therein,

Figure 3 is a front elevation corresponding to Figure 2 but showing the bottle held by its neck,

Figure 4 is a side elevation of the same apparatus showing the gas delivery device brought down into sealing engagement with the lip of the bottle which is held by its neck, and

Figure 5 is a plan view of Figure 4.

Figures 6 to 13 are detailed views on a different 35 scale. Figures 6 and 7 are enlarged plan views of the bottle neck holding device in its open and closed positions respectively,

Figure 8 shows foot-operated means, and

Figure 9 shows cam operated means for bringing the gas delivery device into sealing engagement with the lip of a bottle,

Figure 10 is a side elevation, and

Figure 11 is a plan view of a displaceable platform for the bottle, and

Figure 12 is a side elevation partly in section of a bottle platform which is adjustable as to height,

Figure 13 is an elevation showing the counting device.

Referring now to Figures 1-5 of the drawings the 50 machine is mounted on a back plate 1 which may be of wood or metal and is adapted to be hung upon a wall or otherwise secured thereto, for example with the aid of the plate 2. Wings 3 project forwardly at right angles to the sides of the 55

base 1 and are suitably secured thereto, for example by screws 4. The gas delivery device 5 has trunnions 6 working in slots 7 in the wings 3 and is supported by springs 71 secured to the wings 3 and is also provided with pins 8 projecting through slots 9 in the wings 3. The upper sides of the pins 8 contact with the under-faces of a pair of levers 10 pivoted to the base 1 at 11 and connected together at their outer ends by a handle 12. A pair of catch levers 13 pivoted to the base 1 at 14 are connected at their outer ends by a catch strip 15 adapted to engage with a serrated portion 16 of the levers 10.

10 12. A pair of catch levers 13 pivoted to the base 1 at 14 are connected at their outer ends by a catch strip 15 adapted to engage with a serrated portion 16 of the levers 10.

Beneath the gas delivery device 5 there is provided a bottle neck holding device 17 secured to the base 1. This is illustrated in greater detail in Figures 6 and 7. There is also provided a platform 18 also secured to the base 1 and either the neck holding device 17 or the platform 18 may 20 be used for supporting a bottle beneath the gas delivery device 5. The platform 18 may be adapted to be secured in various positions on the base 1 according to the size of the bottle to be held.

Hingedly secured to the lower part of the base 1 at 19 is a cover 20 which may be swung outwardly and downwardly as shown in Figure 2. A V-shaped strip 21 secured at its ends to the levers 10 serves to hold the casing 20 in the closed position when the levers 10 are depressed.

30 A locking plate 22 is freely pivoted at 23 to one of the wings 3 and is provided with a slot 24 adapted to engage with the pins 8 of the gas delivery device 5 locking it against vertical displacement. The stop plate 22 is adapted to be engaged by the edge 25 of the top plate 26 of the cover 20 so as to displace it out of engagement with the pins 8.

Projecting from the lower end of the gas delivery device is a tube 28 which communicates with the hollow interior thereof. A pressure gas tube 40 40 passes through the gas delivery device 5 and through the tube 28 terminating in a fine nozzle 29. The upper end of the tube 27 is connected through valve 31 provided with handle 32 with a pipe 33 adapted to be connected to a cylinder or other source of carbon dioxide under pressure, for example by coupling 30. A snift pipe 34 communicates with the upper part of the gas delivery device 5 through a snift valve 35 and is connected to a spray trap 36 which is in communication with 50 the atmosphere.

The snift control valve 35 is adapted to be opened by a spring controlled press button 37.

The tube 28 is surrounded by a sleeve 38 in which is housed a washer 39 of rubber or the like flexible material adapted to effect sealing engagement with the lip of a bottle 40 placed therebeneath. A counter 41 adapted to be actuated by movement of one of the trunnions 6 is mounted on one of the wings 3 to register the number of movements of the gas delivery device 5.

Referring now to Figures 5 and 6 the neck-holding device 17 comprises a plate member 42 provided at its front with a cutaway portion 43. To the plate member 42 are pivotally secured by 65 the studs 44 smaller plate members 45 which themselves have cutaway portions 46. Stops 47 are provided on the plate member 42 to limit the rotation of the plate members 45. In the position shown in Figure 6 the cutaway portions of the plate members 45 present an opening wide enough to admit the neck 48 of the bottle 40 but in the position shown in Figure 7 the edges of the cutaway portions 46 are adapted to engage with the under side of the bulge 49 above the neck 48 of 75 the bottle 40.

The counter 41 is shown more clearly in Figure 13. The spindle 72 is provided with a projection 73 adapted to be held up by washer 74 on the end of trunnion 6 projecting through wing 3. A tension spring 75 secured to wing 3 by screw 76 and to spindle 72 by screw 77 rotates the spindle in an anti-clockwise direction each time the trunnion 6 is lowered. The upward movement of the trunnion 6 restores the spindle 72 to its normal position.

10 The operation of the device illustrated in Figures 1-7 is as follows. Referring to Figure 2 the cover 20 is swung down and the bottle 40 filled with liquid to be carbonated is slid around the tube 27 and then pressed into engagement with the plates 45 of the neck holding device 17. This causes the plates 45 to rotate into the position shown in Figure 7 when the bottle is held as shown in Figure 3. During the inward movement of the bottle 40 into the neck holding device 20 17 the gas delivery device 5 is swung from the position shown in Figure 2 into the position shown in Figure 1. Meanwhile, however, the pins 8 which were held by the left hand portion of the slots 9 on the wings 3 are now held by the slot 24 25 in the swinging catch plate 22. The cover 20 is then swung up into position and the edge 25 displaces the catch plate 22 from engagement with the pin 8. A downward movement of the handle 12 carrying with it the levers 10 which bear 30 against the pins 8, presses the gas delivery device 5 down until the washer 39 is in sealing engagement with the lip 50 of the bottle 40.

The V-shaped strip 21 engages the front face of the cover 20, holding it in position. Meanwhile 35 the catch levers fall outwards by gravity until the catch strip 15 engages with the serrations 16 in the levers 10, locking these levers in position.

The handle 32 of the gas valve 31 is now rotated anticlockwise so that carbon dioxide under pressure passes through the tube 27 and nozzle 29 into the liquid in the bottle 40. When sufficient gas has been introduced the handle 32 is rotated in a clockwise direction to close the valve 31. The press button 37 of the snifting valve 35 is then 45 pressed and the surplus gas escapes from the bottle 40 through the pipe 28 and the hollow space in the vessel 5. Any spray is trapped in the trap 36.

It will be seen that the gas delivery device 5 is 50 locked in sealing engagement with the bottle 40 and the cover 20 is locked in position in front of the bottle 20 while the valves are being manipulated.

When the snift valve has been opened the 55 handle 12 is pressed down sufficiently to release the cross member 15 and the levers 13 are then pressed back. The springs 71 lift the gas delivery device 5 out of engagement with the bottle 40 carrying with it the levers 10. The V-shaped 60 member 21 is raised from engagement with the front face of the front cover 20 and the latter can then be dropped again into the position shown in Figure 2 permitting the bottle 40 to be withdrawn and sealed with a Crown cork or the like. It will 65 be seen that on removal of the bottle from the neck holding device, the said device is left in the open position shown in Figure 6 ready for reception of the next bottle. A light spring 51 may, if desired, be provided to enable the plates 45 of the 70 neck holding device 17 to be maintained normally in the open position but this is not essential.

In the case where the bottle 40 is not provided with a bulge 49 by which it can be retained in the neck holding device 17 the platform 18 may be 75

utilized to support the bottle by its base. The platform 18 may be arranged to be adjustable into different positions on the base 1 or can be arranged to be displaced laterally therefrom as shown in Figures 10 and 11. In these figures the base 83 is mounted in a bracket 52, secured to base 1, by pins 53 engaging with slots 78 and pins 19 engaging with recesses 80. By means of handle 81 pins 19 can be lifted out of recesses 80 and pins 10 53 moved along slots 78 until the platform 83 can drop into the position shown in dotted outline in Figure 10. Alternatively as shown in Figure 12 a fixed bottom 54 may be secured to the base 1 carrying the cover 20 pivoted at 55 and having a 15 threaded aperture 56 through which passes a threaded rod 57 carrying at its upper end the platform 84 which may be fitted to the casing 20. To the lower end of the threaded rod 57 is secured a hand wheel 58 for rotation thereof to raise and 20 lower the platform 84.

If desired also the manually operated handle 12 and the catch levers 13 may be replaced by the foot operated device shown in Figure 8 which comprises an elongated saddle member 59 pivotaly secured to the levers 10. Alternatively levers 82 may be provided as shown in Figure 9 which are adapted to be pressed down by eccentrics 60 pivotaly secured to the wings 3 by pins 61 and rotatable by levers 62, 63.

30 I declare that what I claim is:—

1. Apparatus for carbonating liquids in bottles comprising means for supporting a bottle in an upright position, a gas delivery device mounted to pivot about a horizontal axis and move in a vertical direction, a gas delivery tube projecting downwardly therefrom and adapted to be inserted within said bottle when said gas delivery device is swung outwardly on its horizontal axis from above said bottle supporting means and adapted 40 to extend within said bottle when swung over said bottle supporting means, a shield adapted to cover said bottle when held by said supporting means and means for pressing said gas delivery device downwardly into gas-tight engagement 45 with the lip of said bottle when held by said supporting means.

2. Apparatus as claimed in claim 1 in which said shield is adapted to be secured against displacement from the open front face of said casing by a locking device operated by said gas delivery device in its downward movement.

3. Apparatus as claimed in claim 1 in which said gas delivery device has an annular resilient washer surrounding said downwardly projecting gas delivery tube adapted to contact with the lip of the bottle for sealing said gas delivery device into gas-tight engagement with said lip.

4. Apparatus as claimed in claim 1 in which the means for supporting the bottle in the up-

right position comprises a pair of flat plates independently pivoted to move in a common plane and having arcuate cut-out portions adapted when face to face substantially to surround the neck of said bottle and to engage with the underside of the bulge on said neck and when displaced to permit said neck to be withdrawn laterally from between said cut-out portions.

5. Apparatus as claimed in claim 1 including valve means associated with said gas delivery device to enable said gas delivery device to be put into communication with a source of carbon dioxide under pressure or into communication with the atmosphere.

6. An apparatus for carbonating liquids in bottles comprising means for supporting a bottle in an upright position, a gas delivery device, pivotal about a horizontal axis and downwardly displaceable in a plane through the axis, a gas delivery tube projecting downwardly from said gas delivery device and adapted to extend within said bottle when held by said supporting means, and means for pressing said gas delivery device downwardly into gas-tight engagement with the lip of said bottle when held by said supporting means.

7. Apparatus for carbonating liquids in bottles comprising means for supporting a bottle in an upright position, a gas delivery device mounted above said supporting means, a gas delivery tube projecting downwardly from said gas delivery device and adapted to extend within said bottle when held by said supporting means, a casing to receive and hold said bottle when held, having an open front face, a shield adapted to cover said open front face, and to be secured against displacement from the open front face of said casing by a locking device operated by said gas delivery device, and means to press said gas delivery device downwardly into sealing engagement with the lip of said bottle when held by said supporting means.

8. Apparatus for carbonating liquids in bottles comprising means for supporting a bottle in an upright position consisting of means to substantially surround the neck of the bottle and engage with the bulge thereabove, a gas delivery device mounted above said supporting means, a gas delivery tube projecting downwardly from said gas delivery device and adapted to extend within said bottle when held by said supporting means, a casing to receive and hold said bottle when held, having an open front face, a shield adapted to cover said open front face, and means to press said gas delivery device downwardly into sealing engagement with the lip of said bottle when held by said supporting means.

GEORGE FRANCIS SUGDEN.
